CLAIM

The ornamental design for a combined rocker on-off switch and tactile dimmer switch, as shown and described.

DESCRIPTION

FIG. 1 is a perspective view of a combined rocker on-off switch and tactile dimmer switch showing our new design, the broken line showing of the switch being for illustrative purposes only;

FIG. 2 is a front elevation view thereof;

FIG. 3 is a left side elevation view thereof, the right side being a mirror image;

FIG. 4 is a top plan view thereof; and,

FIG. 5 is a rear elevation thereof.
